ABSTRACT

A projection lamp for use in a motion picture projection system. The lamp comprises a primary incandescent filament one end of which is electrically connected to a lamp lead-in, a first ballast filament one end of which is electrically connected to a lamp lead-in, with the other ends of these filaments being electrically connected. The improvement comprises disposing within the lamp a second ballast filament one end of which is serially electrically connected to the primary incandescent filament and the first ballast filament, and the other end is connected to an individual lead-in. The second ballast filament is thus adapted to be connected as part of the series load with the operating potential applied thereacross to cause the primary filament to incandesce with a low level of intensity to permit an individual film frame to be viewed.

LAMP TO ELIMINATE SINGLE FRAME CURTAIN

BACKGROUND OF THE INVENTION

The incandescent projection lamps used with motion picture film projection systems are high-intensity light sources which develop a considerable amount of heat. When the projection system operator wishes to stop the film at a particular frame for individual viewing the heat of the standard projection lamp is so intense that if reviewed for more than a few seconds the film will be damaged or destroyed. It has therefore been the practice to provide a mechanically operated "light curtain" which can be moved into position between the projection lamp and the film when the film is stopped. This "light curtain" in effect acts as a heat shield, and also significantly diminishes the light available for projection of the film image when the film is stopped.

This mechanically operated "light curtain" has proven unreliable in operation and expensive to manufacture. It is therefore desired to protect the stopped single frame of the motion picture film in a simple and reliable manner.

It is now common practice to provide motion picture projection lamps with a ballast filament in conjunction with the primary incandescent filament. The ballast filament meets a variety of design considerations including prevention of arcing when the primary filament fails, and allowing more accurate focusing of primary filament. The ballast filament itself is not generally used to provide light output.

SUMMARY OF THE INVENTION

It has been determined that a unique and convenient way of providing a projection lamp which is conveniently operable for motion picture viewing or for stop action viewing is had by providing a lamp containing not only a primary incandescent filament and a first ballast filament, but also a second ballast filament. The primary incandescent filament of predetermined impedance is permanently serially electrically connected to the first ballast filament of predetermined impedance with the other ends of these filaments being connected to a first lead-in and a second lead-in. A second ballast filament of predetermined impedance has one end serially electrically connected to the first ballast filament and the primary incandescent filament. The other end of the second ballast filament is connected to a third lead-in. An operating potential is applied across the first and second lead-ins to provide a high level of illumination for viewing the moving frames of the motion picture film. The third lead-in and one of the first and second lead-ins which is electrically connected to said second ballast filament through said primary filament and first ballast filament are adapted via conventional switching means to be connected across the operating potential. The first or second lead-in being used results in the serial electrical connection of the primary filament and the first and second ballast filament, and the connection of the three filaments as a serial load impedance across the operating potential. The primary filament will then incandesce at a lower level of illumination for long term viewing of an individual frame of film.

BRIEF DESCRIPTION OF THE DRAWING

FIG. 1 is a schematic showing an example of the lamp of the invention incorporated into a motion picture projection system.

FIG. 2 is a side elevational view of a lamp embodiment of the present invention.

FIG. 3 is a front elevational view of a lamp embodiment of the present invention.

DESCRIPTION OF THE PREFERRED EMBODIMENT

The projection system 10 shown in FIG. 1 comprises the reels 12 for disposing and feeding the film 14, a drive system 16 for moving the reels and the film, the projection lamp 18 of the present invention, and the optical system 20 for projecting the film image. The power supply 22 provides electrical poten-

tial for operating the lamp 18 and also the drive system 16. A switching means 24 connects the power supply to the lamp and the drive means.

The lamp 18 as shown in FIG. 2 and FIG. 3 comprises a hermetically sealed envelope 26 of light transmissive material. The electrical lead-ins 28a, 28b and 28c are hermetically sealed through the base of the envelope 26, and the portion of the lead-ins within the lamp serve to support the interiorly disposed lamp members. A first lead-in conductor 28a is electrically connected to one end of the primary incandescent filament 30, which is centrally disposed within said envelope to facilitate focusing the light output. The other end of this primary filament 30 is electrically connected to one end of the first ballast filament 32, the other end of filament 32 is electrically connected to second lead-in conductor 28b. The external portions of lead-ins 28a and 28b are adapted to be connected via switching means 24 to the power input source 22 which is typically 120 volts AC. The second ballast filament 34 is disposed within the envelope, with one end of the second ballast filament 34 directly electrically connected to the end of the first ballast filament 32 at lead-in 28b, and the other end of the second ballast filament 34 is electrically connected to third lead-in conductor 28c which is also connected to switching means 24. Thus, the filaments are adapted so that the operating potential can be applied across the primary filament 30 and the first ballast filament 32 at lead-ins 28a and 28b, or across all three filaments in series at lead-ins 28a and 28c. When the operating electrical potential is applied to the drive system 16 so that the film is advancing at the normal rate, the switching means 24 causes the lamp potential to be applied across lead-ins 28a, 28b so that the primary incandescent filament and the first ballast filament comprise the load. When there is no electrical potential applied to the drive system 16, the switching means 24 causes the lamp potential to be applied across lead-ins 28a, 28c so that all three filaments comprise the load. By way of example, for a typical 150 watt lamp, about 90 watts is expended in the primary filament and about 60 watts in the first ballast filament when an alternating current potential of 120 volts is applied across lead-ins 28a and 28b. When the second ballast filament is included in the series network by applying the operating potential across lead-ins 28a and 28c, the power expended in the primary incandescent filament is only about 29 watts, about 20 watts for the first ballast filament, and about 36 watts for the second ballast filament.

The lamp embodiment shown incorporates an integral reflector 36, which is designed to accurately focus the light output of the primary incandescent filament 30 for projecting the film image for viewing. The reflector could, of course, be disposed outside the lamp envelope.

The relative impedance for each of the filaments within the lamp are a matter of simple design change depending on the specific operating requirements for the lamp.

Another advantage in using the lamp of the present invention in the improved projector system is the greatly increased light output which can be provided by thus eliminating the light curtain. It has been found possible to double the light output available for still or single frame projection using the lamp of the present invention.

I claim:

1. In a projection lamp for use in a motion picture projection system, which lamp comprises, a sealed light transmissive envelope, a plurality of electrical lead-ins sealed through said envelope, a first lead-in is electrically connected to one end of a single primary incandescent filament of predetermined impedance disposed within said envelope to facilitate focusing the light output and which is serially electrically connected to one end of a first ballast filament of predetermined impedance disposed within said envelope, the other end of said first ballast filament being electrically connected to a second lead-in, the improvement comprising disposing a second ballast filament of predetermined impedance within said envelope, one end of said second ballast filament is serially electrically con-

nected to said primary incandescent filament and said first ballast filament, the other end of said second ballast filament being connected to a third lead-in, said first and second lead-in conductors are adapted to be connected across a source of operating potential of predetermined magnitude to cause said primary incandescent filament to incandesce with a predetermined high level of illumination for viewing moving frames of motion picture film, and said third lead-in conductor and the one of said first and second lead-in conductors which is electrically connected to said second ballast filament through said primary filament and first ballast filament adapted to be connected across said source of operating potential, whereby when so connected said primary filament incandesces with a lower level of illumination for long term viewing of an in-

dividual frame of said film.

2. The lamp as specified in claim 1, wherein a parabolic reflector is disposed within said envelope and said primary incandescent filament is disposed about the focus of said parabolic reflector.

3. The lamp as specified in claim 1, wherein one end of said second ballast filament is directly electrically connected to said other end of the first ballast filament and the other end of the second ballast filament is directly electrically connected to 10 said third lead-in conductor, and said first and third lead-in conductors are adapted to be connected across said source of operating potential for long term viewing of an individual frame of said film.
